UNITED STATES PATENT OFFICE

ALBERT F. HOFFMAN, OF NEWARK, NEW JERSEY, ASSIGNOR TO HOFFMAN BEVERAGE COMPANY, OF NEWARK, NEW JERSEY, A CORPORATION OF NEW JERSEY

FOIL REMOVER

Application filed April 6, 1929. Serial No. 353,033.

The invention relates to apparatus for removing foil from the necks of bottles, as for example, in conditioning bottles for re-use.

The general object is to provide simple and efficient apparatus which is easily and quickly operated to thoroughly remove foil from bottle necks, and which is practically automatic in operation, requiring only the proper positioning of the bottle, whereupon the removing operation is automatically effected.

The characteristics and advantages of the invention are sufficiently explained in connection with the following detail description of the accompanying drawings, which shows one representative embodiment. After considering this example, skilled persons will understand that many variations may be made without departing from the principles disclosed, and I contemplate the employment of any structures that are properly within the scope of the appended claims.

In the drawings:

Fig. 1 is a side elevation of a machine embodying the invention in one form.

Fig. 2 is a top plan.

Fig. 3 is an enlarged elevation of the cleaning or scraping mechanism proper, with some parts in section.

Fig. 4 is a bottom plan of the same.

Fig. 5 is a section at 5—5, Fig. 3.

Fig. 6 is an elevation of a modified scraper arrangement.

Fig. 7 is a top plan thereof.

Fig. 8 is an elevation of another modified scraper arrangement.

Fig. 9 is a top plan thereof.

Fig. 10 is a side elevation (with some parts in section) of a modification of the general machine structure or arrangement.

Fig. 11 is a rear elevation of the same.

Fig. 12 is a sectional detail at 12—12, Fig. 10.

In the form shown in Figs. 1 to 5, the machine includes a column 1 on a base 2, which has a seat or bottle support 3 to approximately or accurately position the bottle 4 for cleaning. The column has arms 5 terminating in bearings 6 for a tubular spindle 7 which is fixedly connected to the hub 8 of a pulley 9, the pulley hub being located between

the adjacent faces of the bearings 6. At the sides of the column guide pulleys 10 are mounted on stub shafts 11, and a driving belt 12 runs over the drive pulleys and around pulley 9 to drive the spindle. The belt may lead from any suitable driving pulley. A shaft 14 is mounted to slide in spindle 7 and is connected to rotate with pulley 9 by a keyway 15 and a key 16. The shaft is reciprocated by a lever 18 fulcrumed at 19 in lugs 20 at the top of the column. The lever has a fork 21 engaging between flanges 22 at the upper end of the shaft. The other end of the lever is connected by a link 23 to a crank 24 on a shaft 25 which rotates in a bearing 26 at the rear of the column. At the other end of shaft 25 is a pulley 27 driven by a belt 28 from any suitable driver such as a pulley on a counter shaft. If desired, the belt systems which drive pulleys 9 and 27 may be inter-connected; that is, there may be a single belt operating both pulleys; otherwise, separate belts may be controlled as desired without regard to its speed of rotation.

A cutter head 30 is secured on the lower end of shaft 14 as by taper pin 31. This head is designed to carry a plurality of cleaner or scraper arms and scrapers, four of these elements being provided in the present embodiment. Head 30 therefore has four sets of spaced lugs 32, and a cutter arm 33 is pivotally mounted on a pin 34 between each pair of lugs. The lower end of each arm has a slot 35 arranged at an angle to the axial plane of the shaft, and a cutter 36 is revolvably mounted in the slot on a pin 37. The cutters are in the form of discs with beveled peripheries 38 providing sharp cutting edges 39 located at the forward edges of the discs in the direction of rotation, as indicated by the arrow in Fig. 4. The arms are normally urged convergently by suitable spring means, one such means consisting in the helical or coiled spring 40 arranged as a band encircling the arms and located in grooves 41 in the outer faces of the arms. Convergent movement of the arms may be limited, as by engagement with faces 42 of the head between the pivot lugs 32.

In operation the shaft is reciprocated, to

raise and lower the scraper head and scrapers, by the crank mechanism described, and is also continuously rotated. When the head is elevated as indicated in dotted lines in Fig. 1, a bottle is placed in position, and the head descends, bringing the cutters in contact with the upper end of the neck, and as the head continues to descend the cutters follow helical paths over the upper portion of the bottle, including all of the neck, such paths being indicated in dotted lines at 45, Figs. 1 and 3, so that by a scraping or milling action the foil is quickly and completely removed. Thereupon, the head is retracted, the bottle removed, another one positioned, and so on. The spring action of the cutter arms permits the cutters to closely follow the contour of the bottle neck in an obvious way. It will also be noted that the scraping or cleaning action takes place both on the downward and upward movement of the head, the course of the cutters in the upward movement being in spiral paths inclined oppositely to the inclination of the dotted lines in the drawings.

Figs. 6 and 7 show a modification of the scraper arrangement, in which the discs 36, instead of being arranged to rotate in vertical planes, as in Figs. 1 to 4, are located in planes inclined substantially (as shown, at an angle of about 45°) to both vertical and horizontal planes, and also so arranged that the plane of a disc is at right angles to a vertical plane through the tangent between the disc and the bottle. Figs. 8 and 9 illustrate a further modification, in which the disc planes are also at an angle to a vertical plane through the tangent between the disc and the bottle. Either of these arrangements enables arcuate sectors of the disc edges to more closely conform to the different portions or contours of the bottle-neck, as clearly shown in Figs. 6 and 8.

Figs. 10 to 12 illustrate a modification of the general organization of the machine, in which the scraper head 30 is revolvable, but fixed against vertical motion in an arm 50 of frame or column 51, and a bottle support 52, in which the base of the bottle is centered, is arranged for vertical movement, along with its supporting plunger 53. The plunger reciprocates in a guide hole in a frame arm 54, and in a sleeve 55 formed in the base 56. A lever 57, fulcrumed in the column at 58, has a rounded end 59 engaging in a slot in plunger 53, and has its other end connected by a link 60 to a crank 24 on a drive shaft 25, similar to the crank and shaft identified by the same numerals in Figs. 1 and 2. The bottle support 52 has an upright 65 to which is secured means for bracing or centering an upward part of the bottle, near the lower end of the foil-covered zone of the neck. Such means is specifically, as shown, a block 66 of sponge rubber, or similar material, to give a cushioning support to the bottle 6, and hav-

ing a socket formation 67, open at the front, to properly receive and center the bottle, and by frictional engagement, to prevent or assist in preventing, rotation of the bottle.

The operation is, in result, generally equivalent to that of the first form, except of course in this case the traversing of the foiled neck of the bottle in relation to the scrapers, is effected by movement of the support 52, under control of crank 24, link 60 and lever 57.

I claim:

1. Scraping apparatus for purposes described, comprising a cleaner having annularly arranged scraping elements, means for moving the cleaner vertically, and means for concurrently rotating the cleaner, said elements being revoluble discs having beveled peripheries providing sharp scraping edges. 70

2. Scraping apparatus for purposes described, comprising a cleaner having annularly arranged scraping elements, means for moving the cleaner vertically, means for concurrently rotating the cleaner, said elements being revoluble discs mounted in planes angular to the rotation axis of the cleaner, and means to force said elements toward the axis of rotation of the cleaner when said elements are in use. 85

3. Apparatus of the class described, comprising a column, a spindle mounted for rotation thereon, means for rotating the spindle, a shaft connected in the spindle to rotate therewith and also to reciprocate therein, means for automatically reciprocating the shaft, a head on the shaft, spaced scraper arms pivoted in the head, a scraper carried by each arm, and means resiliently urging the arms convergently, the scrapers being discs revolvably mounted in the ends of the arms. 100

4. Apparatus of the class described, comprising a column, a spindle mounted for rotation thereon, means for rotating the spindle, a shaft connected in the spindle to rotate therewith and also to reciprocate therein, means for reciprocating the shaft, a head on the shaft, spaced scraper arms pivoted in the head, a scraper carried by each arm, and means resiliently urging the arms convergently, the scrapers being discs revolvably mounted in the ends of the arms, and rotatable in planes oblique to the shaft axis. 110

5. Apparatus of the class described, comprising a column, a spindle mounted for rotation thereon, means for rotating the spindle, a shaft connected in the spindle to rotate therewith and also to reciprocate therein, means for reciprocating the shaft, a head on the shaft, spaced scraper arms pivoted in the head, a scraper carried by each arm, and means resiliently urging the arms convergently, the means for reciprocating the shaft including a lever fulcrumed on the column 120

and connected to the shaft, and a crank for operating the lever.

6. Apparatus of the class described, comprising a column, a vertical spindle mounted for rotation thereon, means for rotating the spindle, a shaft connected in the spindle to rotate therewith and also to reciprocate therein, means for reciprocating the shaft, a head on the shaft, spaced dependent scraper arms pivoted in the head, a scraper carried by each arm, and means resiliently urging the arms convergently, the scrapers being circular sharpened discs revolvably mounted in the ends of the arms.

15 In testimony whereof I affix my signature.

ALBERT F. HOFFMAN.
